United States Patent

Des. 240,464
Patented July 6, 1976

240,464

MEDICINAL APPLICATOR OR THE LIKE

Barry H. Dash, Englewood Cliffs, N.J., assignor to American Home Products Corp., New York, N.Y.

Original design application May 8, 1974, Ser. No.
468,050. Divided and this application Sept. 22,
1975, Ser. No. 615,323

Term of patent 14 years

Int. Cl. D24—02

U.S. Cl. D83—12 A

FIG. 1 is a front elevational view of a medicinal applicator or the like showing my new design;

FIG. 2 is an exploded side elevational view;

FIG. 3 is a top plan view;

FIG. 4 is a top plan view with the closure removed;
and

FIG. 5 is a bottom plan view.

This application is a division of application Ser. No.
468,050, filed May 8, 1974.

I claim:

The ornamental design for a medicinal applicator or the like, substantially as shown.
